PACKAGE FOR SCOURING DEVICES

Edward S. Bradford, Jr., Longmeadow, Mass., assignor to Springfield Wire & Tinsel Co., West Springfield, Mass., a corporation of Massachusetts

Application June 20, 1939, Serial No. 280,096

1 Claim. (Cl. 206—65)

This invention relates to packages in which scouring devices may be shipped and retained during pending sales. The particular scouring device with which the invention is concerned is composed of curled wire masses secured centrally to a wooden handle or knob generally by means of a staple. The curled wire, while strong enough to act as an abrasive in the cleaning of cooking dishes and the like, is of a character which readily takes on a permanent deformation if it is retained for any length of time in lateral contact with other objects.

Formerly these scouring devices have been packed in containers and have been in free contact with each other. It has been found that during shipment and in storage the scouring devices tended to force themselves towards one side or corner of the container and to become distorted. I have found that if the pressure on the device is restricted to the central portion of the curled wire mass no objectionable distortion will occur, and the package to be described has been designed upon this principle.

Referring to the drawing.

Fig. 1 is a top plan view of a filled container with the cover removed;

Fig. 2 is a side view of the filled package with portions of the container and cover broken away.

The package comprises a container 10 having a cover 11 which may be of any desired construction. The securing devices each comprise a curled wire mass 12 secured at its center as by a staple and to a knob 13. As the staple is buried in the curled wire mass it does not appear in the drawing. The curled wire mass is springy and relatively soft in texture except at the center where it is secured to the knob.

In accordance with the invention the devices are arranged within the container in a plurality of layers. The scouring devices in each layer are arranged in two alternating sets, the devices of one set having their curled wire portions

at the bottom and the devices of the other set having their knobs at the bottom. To hold the devices in each layer in the desired arrangement a spacing sheet 14 is provided, having perforations adapted to receive the knobs and spaced to cause the scouring devices to be retained in their desired locations.

The devices are arranged in layers of similar arrangement, thus permitting the knob of one device to make contact only with the central portion of the corresponding device in the next layer. As stated above the central portion is relatively solid and no distortion is thus caused. The scouring devices are prevented from shifting by reason of the spacing sheets, one of which is 15 used for each layer. All injurious contact between the devices themselves and between the walls of the cases are avoided.

I claim:

A package for scouring devices each consisting of a curled wire mass secured centrally to a knob, comprising a container, a layer of scouring devices arranged in alternating sets within the container, the devices in one set having their curled wire portions resting on the container bottom and the devices in the second set having their knobs resting on the container bottom, a spacing sheet having perforations into which the knobs of said devices are fitted to retain them in spaced relation, a second layer of scouring devices also arranged in two alternating sets, each device in one set having the central portion of its curled wire mass resting upon the end of the knob of a device in the lower layer, and each device in the second set having its knob resting upon the central portion of the curled wire mass of a device in the lower layer, and a second spacing sheet having perforations into which the knobs of the devices in the second layer are fitted to retain them in spaced relation.
